(No Model.)

C. C. TAYLOR.
SUSPENSORY GARMENT.

No. 416,970.

Patented Dec. 10, 1889.

UNITED STATES PATENT OFFICE.

CHARLES C. TAYLOR, OF NEW YORK, N. Y.

SUSPENSORY GARMENT.

SPECIFICATION forming part of Letters Patent No. 416,970, dated December 10, 1889.

Application filed April 16, 1889. Serial No. 307,440. (No model.)

To all whom it may concern:

Be it known that I, CHARLES C. TAYLOR, a resident of the city, county, and State of New York, have invented an Improved Suspensory 5 Garment, of which the following is a specification.

The object of this invention is to produce a garment for use in carrying babies, bundles, &c.; and the invention consists in the 10 novel details of improvement and the combinations of parts that will be more fully hereinafter set forth, and then pointed out in the claims.

Reference is to be had to the accompanying 15 drawings, forming part of this specification, wherein—

Figure 1 is a front view of my suspensory garment, shown in position on a person and holding a child. Fig. 2 is a back view of my 20 garment in position on a person. Fig. 3 is a back view of a modification, and Fig. 4 is a front view of a modification, both being in position on a person.

Referring now to the drawings, the letter 25 A represents a body or waist, that is shown as made of netting, but it may be made of other suitable material. The waist A is provided with a belt B, to be fastened around the waist of a person by a buckle or otherwise. From the shoulder portion of the waist A a strip of netting or the like D extends forward, as in Fig. 1. This strip D may be a continuation of the back of the waist or body A, if desired. Any draft that is applied to 30 the strip D will be communicated to the belt B, and also distributed over the back of the person. From the belt B, at the front of the waist or body A, depends an apron or strip E, substantially similar to the strip D, the 35 apron or strip E being preferably made of the same material as the strip D. The apron or strip E carries at its free end a buckle b, while the strip D carries a strap a to engage the buckle b, or vice versa, whereby the ends 40 of the strip D and apron E can be readily connected to form a loop or pocket in which to carry a baby, package, or the like; but the ends of the strip D and apron E can be con-

nected otherwise than by the buckle a and strap b, if desired. As shown in Fig. 4, the 50 apron E carries the strap b, while the strip D carries the buckle a.

When desiring to carry a baby, package, or the like, the garment is placed upon the person and the ends of the strip D and apron E 55 are united, whereby a pocket is formed that extends from the belt B in front up to the shoulder, whereby the weight that is placed in the pocket thus formed is supported partially by the belt B in front and partially by 60 the shoulder, and is also distributed over the back, as before stated.

When desired, the body or waist A may be lined with a suitable material. If desired, the parts B, D, and E can be used without 65 the body or waist A, in which case the strip D would extend from the belt B up over the shoulder, as shown in Fig. 3. In this case the ends of D and E will be united to form the pocket, as before stated. In Fig. 4 two 70 strips D are shown extending over the shoulders, and two aprons E are shown carried by the belt B, to be united with said strips; but it is evident that one or more could be used, as desired. Instead of the apron E being attached to the belt B in front, it could be attached thereto at the side or back, in which 75 case the position of the strip D would be correspondingly changed, so as to support a package in connection with the apron E. If 80 desired, the sides of the apron E could be made of wire or analogous firm material, so as to prevent too great pressure upon the person.

By using netting for my suspensory garment the same can be made light and still 85 have great strength, while the strands of the netting will conform to the shape of the body and distribute the strain over a large area.

Having now described my invention, what 90 I claim is—

1. As a new article of manufacture, a suspensory garment consisting of the belt B, adapted to pass around a person's waist, strip D and apron E, united together by the belt, 95 as described, the strip D being adapted to

pass from the belt B over the shoulder, and means, substantially as described, for connecting the free ends of the strip D and apron E, as specified.

- 5 2. The body or waist A, having belt B, adapted to pass around a person's waist, combined with the strip D, for passing from the belt over the shoulder, and the apron E, both

connected with the belt B, and means, substantially as described, for uniting the free ends of the strip D and apron E, as specified.

CHARLES C. TAYLOR.
